HOT-WATER HEATER FOR ARMY USE

James L. Breese, Santa Fe, N. Mex., assignor to
Oil Devices, Santa Fe, N. Mex., a limited partnership of Illinois

Application February 19, 1944, Serial No. 523,077

14 Claims. (Cl. 122—17)

My invention relates to an improvement in hot water heaters and has for one purpose to provide a heater adapted for use with a generator type burner in which the rate of combustion is controlled by controlling the rate of flow of air to a fuel container. Another purpose is to provide improved thermostatic control means for controlling the burner of a hot water heater. Another purpose is to provide a readily demountable burner and hot water heater assembly. Another purpose is to provide an improved air supply control means for generator type burners. Other purposes will appear from time to time in the course of the specification and claims.

I illustrate the invention more or less diagrammatically in the accompanying drawing wherein:

Figure 1 is a vertical section;

Figure 2 is a section, on an enlarged scale, on the line 2—2 of Figure 1;

Figure 3 is a section, on an enlarged scale, on the line 3—3 of Figure 1 and

Figure 4 is a section, on an enlarged scale, on the line 4—4 of Figure 1.

Like parts are indicated by like numbers throughout the specification and drawing.

Referring to the drawing, 1 generally indicates a fuel supply container which has a removable top 2. Secured to the top is an air inlet tube 3 having one or more longitudinally extending slots 4 which extend both above and below the normal level of the liquid fuel 5 within the container 1 and insure the delivery of a supply of air to the surface of the fuel. 6 indicates a second air inlet tube with a longitudinally extending slot 7. It is provided with a removable cover 8 which may have an adjustable shutter 9 therein, which can be actuated by the nob 10. The cover 2 is provided with a central aperture 11. Secured to the top of the cover 2 is a burner pot 12 having a plurality of primary air inlets 13 located at various levels therein. 14 indicates a top row of secondary air inlets which are preferably larger and more closely spaced and may be upwardly and inwardly inclined. The pot has a bottom 15 centrally apertured as at 16 in alignment with the aperture 11 of the cover 2. The pot is shown as having a top flange 17 to which is secured an outer skirt 18. Air may flow inwardly and upwardly about the lower edge of the skirt 18. 19 is a central apertured flame ring partially closing the top of the pot 12.

20 generally indicates a plurality of supports which are connected at their upper ends by a channel ring 21. 22 is any suitable bottom connection or reinforcement for the supports 20.

23 is the outer wall, herein shown as cylindrical, of a hot water tank. 24 illustrates a cylindrical inner wall which also defines a central heating chamber aligned with and in communication with the interior of the pot 12. The hot water tank is completed by a bottom member 25 and a top member 26. The means for admitting and removing water from the tank are not shown, but it will be understood that any suitable means for supplying it with cold water and for removing the heated water may be employed. 27 is any suitable top closure ring with a central flange 28 defining a flue passage. 29 is any suitable flue member which may be removably positioned thereabout. A centering member or members 30 may be employed, secured to the bottom member 25 of the tank, and seating in the channel 21. I may employ a circumferentially extending ring, or a plurality of segments or any other suitable supporting devices properly shaped to enter the upward concavity of the channel 21.

31 indicates an air inlet tube the upper end of which is located above the top 26 of the tank and the lower end of which extends below the bottom 25 of the tank. It is provided with an enlarged bottom sleeve 32 which is adapted to telescope with the upward extending end 3a of the air inlet tube 3 of the pot 1. Thus air may be admitted downwardly along the tube 31 to the interior of

30 the fuel container 1. The rate of flow may be thermostatically controlled by one or both of the structures shown in detail in Figures 2 and 4. Referring first to Figure 2 and the corresponding part of Figure 1, 40 indicates a bi-metallic leaf or warping bar mounted in any suitable tube or container 41 secured to the top of the air inlet tube 31. The warping bar 40 is preferably so placed as to respond directly to the heat of the combustion chamber surrounded by the inner wall 24 of the water tank. As the heat of the combustion chamber increases the warping bar 40 warps downwardly and moves the valve member 42 to the position to reduce the inflow of air. Thus overheating of the element and an undue

45 fire rate is prevented, independent of the heat of the water itself. This is desirable, to prevent undue surges of combustion and overheating of the heater itself.

Referring to Figure 4 it illustrates an air control device for the tube 31 which responds relatively directly to changes in the temperature of the water in the tank. I illustrate, for example, a pin 45 extending across the tube 31 and provided with a warping coil 46, one end of which is anchored on the pin and the other is secured to

a pivoted disc or ring 47 with a central aperture 48 and some measure of clearance 49 between its outer edge and the opposed inter-faces of the tube 31. Thus as the heat of the water in the tank increases, the warping element 46 is effective to move the ring 47 to minimum air flow position. Preferably the pin 45 seats or is secured at its end to a ring 50 which is slidable within the tube 31 but is of sufficient tight fit to prevent unintended movement. However, it may be inserted or removed by the employment of any suitable push rod, and may be set at any desired level or position.

It will be realized that whereas I have described and shown a practical and operative device, nevertheless many changes may be made in size, shape, number and disposition of parts without departing from the spirit of my invention. I, therefore, wish my drawing and descriptions to be taken as in a broad sense illustrative and diagrammatic.

The use and operation of my invention are as follows:

The burner shown herein is of the generator type and includes a fuel supply chamber 1, a hydroxylating pot 12, and means for supplying air to the fuel pot. In starting the device I may initiate combustion by removing the cap 8 and dropping a piece of illuminated waste or other suitable material to the surface of the fuel. I may leave the cap off or replace the cap and turn the knob 10 to provide an excess supply of air until combustion is initiated. Since the device is cold, there will also be a maximum air flow through the slots 4 of the tube 3 and combustion will also be supported adjacent to tube 3. When the machine is heated and in operation, the supply of air through the cap 8 may be reduced or cut off.

In the normal operation of the device the pre-combustion which takes place in the chamber 1 vaporizes sufficient fuel to support combustion in the pot 12. This vaporized fuel moves up through the apertures 11 and 16 and receives a primary air supply through the air inlets 13. This mixture then receives its secondary air from the inlets 14. The final mixture burns at or above the top of the pot and the flame flows upwardly through the central aperture of the flame ring 19 and into the space defined by the inner tank wall 24. Once the device is in operation, the rate of combustion is controlled by the rate of flow of air downwardly through the tubes 31 and 3. Overheating of the burner will result in overheating of the flue 29 and the top of the combustion chamber 27 and will actuate the valve 42. When the water reaches a predetermined elevated temperature, the ring 47 is moved by the warping coil 46 to minimum air flow position. Thus overheating of the burner and overheating of the water within the tank are prevented, with a consequent fuel saving.

The structure herein shown is well adapted to outdoors use, for example, to Army use or to camping use. The device may be easily and quickly set up or taken down. The water tank is supported on the supports 20. In setting the device up the supports 20 are first set in position. The burner assembly is then positioned and the water tank is lowered into supported position with the member or members 30 entering the channel 21. The sleeve 32 is slipped about the tube portion 3a, and the device is ready for use. Any suitable flue member 28 is removably positioned about the top flange 28.

I claim:

1. In a hot water heater, a water tank having inner and outer walls, the inner walls defining a heater and flue space, a burner including a liquid fuel storage and vaporizing chamber and a burner pot in communication with the interior of said chamber the interior of the pot being in communication with the interior of said flue space, the burner pot being generally axially aligned therewith and being positioned to close the bottom of said space, means for withdrawing the flue gases from the top of said space, and air supply means for said vaporizing chamber including an air tube extending through said tank to the chamber.

2. In a hot water heater, a water tank having inner and outer walls, the inner walls defining a heater and flue space, a burner including a liquid fuel storage and vaporizing chamber and a burner pot in communication with the interior of said chamber the interior of the pot being in communication with the interior of said flue space, the burner pot being generally axially aligned therewith and being positioned to close the bottom of said space, means for withdrawing the flue gases from the top of said space, and air supply means for said vaporizing chamber including an air tube extending through said tank to the chamber, and means, responsive to temperature changes adjacent the heater, for varying the rate of flow of air through said tube.

3. In a hot water heater, a water tank having inner and outer walls, the inner walls defining a heater and flue space, a burner including a liquid fuel storage and vaporizing chamber and a burner pot in communication with the interior of said chamber the interior of the pot being in communication with the interior of said flue space, the burner pot being generally axially aligned therewith and being positioned to close the bottom of said space, means for withdrawing the flue gases from the top of said space, and air supply means for said vaporizing chamber including an air tube extending through said tank to the chamber, and means, responsive to temperature changes of the liquid in said tank, for varying the rate of flow of air through said tube.

4. In a hot water heater, a water tank having inner and outer walls, the inner walls defining a heater and flue space, a burner including a liquid fuel storage and vaporizing chamber and a burner pot in communication with the interior of said chamber the interior of the pot being in communication with the interior of said flue space, the burner pot being generally axially aligned therewith and being positioned to close the bottom of said space, means for withdrawing the flue gases from the top of said space, and air supply means for said vaporizing chamber including an air tube extending through said tank to the chamber, and means, responsive to temperature changes of the liquid in said tank, for varying the rate of flow of air through said tube, including a valve element in the portion of said tube which passes through said tank, and heat responsive means for varying its effective position.

5. In a hot water heater, a water tank having inner and outer walls, the inner walls defining a heater and flue space, a burner including a liquid fuel storage and vaporizing chamber and a burner pot in communication with the interior of said chamber the interior of the pot being in communication with the interior of said flue

space, the burner pot being generally axially aligned therewith and being positioned to close the bottom of said space, means for withdrawing the flue gases from the top of said space, and air supply means for said vaporizing chamber including an air tube extending through said tank to the chamber, and means, responsive to temperature changes of the liquid in said tank, for varying the rate of flow of air through said tube, including a valve assembly in that portion of the tube which passes through said tank, said assembly including a movable valve element, a heat responsive valve actuating element, and a support on which said assembly is mounted.

6. In a hot water heater, a water tank having inner and outer walls, the inner walls defining a heater and flue space, a burner including a liquid fuel storage and vaporizing chamber and a burner pot in communication with the interior of said chamber the interior of the pot being in communication with the interior of said flue space, the burner pot being generally axially aligned therewith and being positioned to close the bottom of said space, means for withdrawing the flue gases from the top of said space, and air supply means for said vaporizing chamber including an air tube extending through said tank to the chamber, and means, responsive to temperature changes of the liquid in said tank, for varying the rate of flow of air through said tube, including a valve assembly in that portion of the tube which passes through said tank, said assembly including a movable valve element, a heat responsive valve actuating element, and a support on which said assembly is mounted, said support being bodily removable, with the valve assembly, from said tube.

7. In a hot water heater, a water tank having inner and outer walls, the inner walls defining a heater and flue space, a burner including a liquid fuel storage and vaporizing chamber and a burner pot in communication with the interior of said chamber the interior of the pot being in communication with the interior of said flue space, the burner pot being generally axially aligned therewith and being positioned to close the bottom of said space, means for withdrawing the flue gases from the top of said space, and air supply means for said vaporizing chamber including an air tube extending through said tank to the chamber, and means, responsive to temperature changes adjacent the flue space, for varying the rate of flow of air through said tube.

8. In a hot water heater, a water tank having inner and outer walls, the inner walls defining a heater and flue space, a burner including a liquid fuel storage and vaporizing chamber and a burner pot in communication with the interior of said chamber the interior of the pot being in communication with the interior of said flue space, the burner pot being generally axially aligned therewith and being positioned to close the bottom of said space, means for withdrawing the flue gases from the top of said space, and air supply means for said vaporizing chamber including an air tube extending through said tank to the chamber, and means, responsive to temperature changes adjacent the flue space, for varying the rate of flow of air through said tube, including a valve adjacent the top of said tube, and a heat responsive actuating means therefor, located adjacent an upper portion of said flue space.

9. In a hot water heater, a water tank having inner and outer walls, the inner walls defining a

heater and flue space, a burner including a liquid fuel storage and vaporizing chamber and a burner pot in communication with the interior of said chamber the interior of the pot being in communication with the interior of said flue space, the burner pot being generally axially aligned therewith and being positioned to close the bottom of said space, means for withdrawing the flue gases from the top of said space, and air supply means for said vaporizing chamber including an air tube extending through said tank to the chamber, and plural means for controlling the rate of flow of air through said tube including valve means and means for actuating it in response to temperature changes of the water in the tank, and additional valve means and means for actuating it in response to changes in the temperature of said flue space.

10. In a demountable hot water heater a ground engaging support, a water tank removably positioned on said support, said tank having inner and outer generally concentric generally cylindrical walls, the inner walls defining the heater and flue space, a burner pot removably positioned within said support, a generator chamber element secured to and movable with said pot, means for supplying air to said generator chamber including an air tube extending through said tank and an air tube extending upwardly from said generator chamber and a removable telescopic connection between said tubes.

11. In a hot water heater, a water tank having inner and outer generally concentric generally cylindrical walls, the inner walls defining a heater and flue space, a liquid fuel storage and vaporizing chamber axially aligned with said flue space, a burner pot interposed between the flue space and the vaporizing chamber, its interior being in communication with the interior of said flue space and vaporizing chamber, said pot including a circumferential wall having a plurality of air inlet apertures located at various distances from the ends of the pot and air supply means for said vaporizing chamber including an air inlet duct extending through said water tank.

12. In a hot water heater, a water tank having inner and outer generally concentric generally cylindrical walls, the inner walls defining a heater and flue space, a liquid fuel storage and vaporizing chamber axially aligned with said flue space, a burner pot interposed between the flue space and the vaporizing chamber, its interior being in communication with the interior of said flue space and vaporizing chamber, said pot including a circumferential wall having a plurality of air inlet apertures located at various distances from the ends of the pot and air supply means for said vaporizing chamber including an air inlet duct extending through said water tank, and heat responsive control means for said duct adapted to control the rate of flow therethrough.

13. In a hot water heater, a water tank having inner and outer walls, the inner walls defining a heater and flue space, a liquid fuel storage and vaporizing chamber axially aligned with said flue space, a burner pot interposed between the flue space and the vaporizing chamber, its interior being in communication with the interior of said flue space and vaporizing chamber, said pot including a circumferential wall having a plurality of air inlet apertures located at various distances from the ends of the pot and air supply means for said vaporizing chamber including an air inlet duct extending through said water

tank, and heat responsive control means for said duct adapted to control the rate of flow therethrough.

14. In a hot water heater, a water tank having inner and outer walls, the inner walls defining a heater and flue space, a liquid fuel storage and vaporizing chamber axially aligned with said flue space, a burner pot interposed between the flue space and the vaporizing chamber, its in-

terior being in communication with the interior of said flue space and vaporizing chamber, said pot including a circumferential wall having a plurality of air inlet apertures located at various distances from the ends of the pot and air supply means for said vaporizing chamber including an air inlet duct extending through said water tank.

JAMES L. BREESE.
